DESIGN FOR A STORAGE CABINET

Francis John Osuch, Detroit, Mich., assignor to Robot-Hand Corporation, Detroit, Mich., a corporation of Delaware

Application December 12, 1935, Serial No. 60,023

Term of patent 14 years

To all whom it may concern:

Be it known that I, Francis John Osuch, a citizen of the United States, residing at Detroit, in the county of Wayne and State of Michigan, have invented a new, original, and ornamental Design for a Storage Cabinet, of which the following is a specification, reference being had to the accompanying drawing forming part thereof.

The rear and side not shown in the figures in the drawing present substantially plane surfaces.

I claim:

The ornamental design for a storage cabinet, as shown and described.

FRANCIS JOHN OSUCH.
